UNITED STATES PATENT OFFICE.

GEORGE S. BLAKESLEE, OF CHICAGO, ILLINOIS.

WASHING-MACHINE.

1,314,041.

Specification of Letters Patent. Patented Aug. 26, 1919.

Application filed August 24, 1916. Serial No. 116,598.

To all whom it may concern:

Be it known that I, GEORGE S. BLAKESLEE, a citizen of the United States, and a resident of Chicago, in the county of Cook, State of Illinois, have invented certain new and useful Improvements in Washing-Machines, of which the following is a specification, reference being had to the accompanying drawings.

10 My invention relates to washing machines of the type in which a paddle wheel is employed for throwing a stream of water upon and across a series of articles to be washed, which are being carried forward past the 15 paddle wheel by a suitable conveyer. It is one of the objects of my invention to provide a new and improved arrangement of conveyer means; to provide a new and improved arrangement comprising a plurality 20 of paddle wheels adapted to coöperate for washing the articles traveling by upon the conveyer; to provide new and improved means for preventing objectionable splashing of the water; to provide new and improved means in connection with each of the 25 paddle wheels for breaking up and spreading the water thrown upon the articles to be washed; and to improve washing machines of this type in sundry details hereinafter 30 pointed out. The preferred means by which I have accomplished my several objects are illustrated in the accompanying drawings and are hereinafter specifically described. That which I believe to be new and desire 35 to cover by this application is set forth in the claims.

In the drawings:

Figure 1 is a top or plan view of my improved washing machine;

40 Fig. 2 is a longitudinal vertical cross section taken substantially on line 2—2 of Fig. 1;

Fig. 3 is a transverse vertical section through my machine taken substantially on 45 line 3—3 of Fig. 1;

Fig. 4 is an enlarged detail illustrating the means for driving one or more of the paddle wheels, being partly in section, taken on line 4—4 of Fig. 1;

50 Fig. 5 is a view of the parts shown in Fig. 4 as seen from the left in said Fig. 4;

Fig. 6 is a top view of one of the conveyer belts; and

Fig. 7 is a longitudinal section through

the belt of Fig. 6, being taken substantially 55 on line 7—7 of Fig. 6.

Referring to the several figures of the drawings in which corresponding parts are indicated by the same reference characters,—

15 indicates a tank divided by a partition 16 into two compartments 17 and 18, the compartment 17 being adapted to contain washing water provided with a suitable 60 cleaning agent, and the compartment 18 being provided with clean water for rinsing purposes. The tank 15 is supported by means of a suitable framework 19. The water is adapted to be fed to the tank 15 by means of a pipe 20 from any suitable 65 source of supply, valves 21—22 being provided for controlling the supply of water. The water in the compartments 17—18 is heated by steam introduced through a line 70 of piping 23 provided with valves 24—25 for controlling the admission of steam. As best shown in Fig. 2, the pipe 23 is provided at its inner ends with nozzles 26—27 of any suitable type for controlling the entrance of the steam from the pipe 23 to the water in 75 the compartments 17—18. A drain pipe 28 is provided having connection with the tank 15 at intervals along the bottom by means of branches 29, each of which is provided with a suitable valve 30. The drain pipe 28 is also adapted to take care of any overflow 80 from the tank 15 by means of overflow connections 31 leading from the side of the tank 85 at either end thereof.

The tank 15 is provided at each side with 90 two housings, the outer face of each of which is circular, as best shown in Fig. 3, said housings being indicated by the numerals 32, 33, 34 and 35 (see Fig. 1). A shaft 36 extends longitudinally through the housings 95 32—33, having fixedly mounted thereon suitable water wheels 37—38 adapted to work in the housings 32—33. A shaft 39 is likewise mounted in the housings 34—35, said shaft having fixed thereon paddle 100 wheels 40—41 within the housings 34—35. Each of the shafts 36—39 is provided with a gear 42 fixed thereon meshing with a pinion 43 (see Fig. 4) mounted upon a shaft 44 (see Fig. 5) which is journaled at one end 105 in a suitable bearing on the adjacent housing 32—34 and is supported at its other end by a plate or bracket 45 which is also

mounted upon the shaft 36 and is further held in position relative to the said housing 32-34 by means of a bolt 46. Driving wheels 47, preferably in the form of pulleys, 5 are fixed upon the shafts 44 and adapted to be driven in any suitable manner from any suitable source of power.

The conveyer means comprises two endless belts 48-49 (see Fig. 2) one mounted in 10 each of the compartments 17-18. Each of the belts 48-49 comprises a plurality of chains 50 connected together by means of transversely-extending bars 51, preferably having upturned ends as shown in Figs. 3 15 and 6 whereby a lateral flange is provided along each edge of the belt. The chains of the belt 48 are supported by means of sprocket wheels 52 mounted upon transversely-extending shafts 53-54 (see Fig. 2). 20 The chain 48 is driven by means of a sprocket wheel 55 mounted upon the outer end of the shaft 52, as shown in Fig. 1, which is connected by means of a sprocket chain 56 with a sprocket wheel 57 mounted 25 upon a short shaft 58 which is connected by any suitable gearing with the shaft 36, such gearing being located within a housing 59 as shown in Fig. 1.

The chains 50 of the belt 49 are supported 30 by means of sprocket wheels 60 mounted upon transversely-extending shafts 61-62. The chain 49 is driven from the chain 48 by means of a sprocket wheel 63 mounted upon an extending end of the shaft 61 connected 35 by means of a sprocket chain 64 with a sprocket wheel 65 mounted upon an extending end of the shaft 54 (see Fig. 1).

The upper portions of the belts 48-49 are supported by longitudinally-extending 40 bars 66 which in turn are supported by means of brackets 67 connected with transversely-extending bars 68 removably secured between the side walls of the tank by means of brackets 69 (see Figs. 2 and 3).

45 With the belts 48 and 49 being driven by the means above described so as to move the upper portions of said belts to the right in Figs. 1 and 2, the paddle wheels 37 and 38 will be driven in counterclockwise direction in Fig. 3 so as to throw a continuous supply of water toward the said belts. At the same time the paddle wheels 40-41 are to be rotated in proper direction to throw a continuous supply of water toward 50 said belts, the rotation of the wheels 40-41 in the construction shown being in counterclockwise direction in Fig. 3. While the drawings show the paddle wheels at one side operating to throw the water upward 55 from the lower portions of the wheels and the wheels at the other side operating to throw the water downward from the upper portions of the wheels, it will be understood that the arrangement may be reversed 60 in whole or in part as desired whereby the 65

water is thrown toward the conveyer belts by either the lower portions or the upper portions of the wheels, as is well understood in the washing machine art.

For preventing splashing of the water 70 from one to the other of the compartments 17-18 and from the outer ends of said compartments, I have provided curtains 70, 71, 72 and 73 of any suitable type, said curtains being preferably hung from the 75 upper wall 74 of the tank. Each of the curtains preferably comprises a plurality of pendants arranged close together so that any article being carried through the machine upon the conveyer belts will have 80 free movement without danger of tearing the curtains. I have found that a plurality of closely associated chains or cords is effective for preventing the escape of water while at the same time giving free movement to the articles to be washed.

For breaking up and spreading the water thrown by the paddle wheels 37, 38, 40 and 41 so as to cause such water to reach every portion of the tank between the oppositely-disposed wheels, I have provided large-meshed screens 75 of any suitable type through which the water is thrown from the housings upon the conveyer belts.

My improved machine is designed primarily for washing castings such as mud-guards or other automobile parts, but I do not wish to be restricted to such use of my machine which is adapted for a great variety of work, as will be readily understood.

What I claim as my invention and desire to secure by Letters Patent, is—

1. A washing machine comprising a tank adapted to contain water, means for supporting the articles to be washed, and paddle wheels opposite each other at opposite sides of said tank for throwing water from said tank upon the articles to be washed, one of said paddle wheels being arranged 105 to throw water upward and across the articles, and the other to throw it downward and across said articles.

2. A washing machine comprising a tank adapted to contain water, means for supporting the articles to be washed while they are moved over the water in said tank, and paddle wheels at opposite sides of said tank for throwing water therefrom upon the articles to be washed, one of said paddle 115 wheels being arranged to throw water upward and across the articles and the other to throw it downward and across said articles.

3. A washing machine comprising a tank 125 adapted to contain water, means for supporting the articles to be washed while they are moved over the water in said tank, and paddle wheels opposite each other at opposite sides of said tank for throwing water 130

therefrom upon the articles to be washed, one of said paddle wheels being arranged to throw water upward and across the articles and the other to throw it downward 5 and across said articles.

4. A washing machine comprising a tank divided transversely by a transverse partition into separate compartments, conveyer belts in said compartments over the water therein, the inner end portions of said belts being adjacent to said partition whereby the articles to be washed are delivered by one of said belts to the other, and means 10 for driving said belts.

15 5. A washing machine comprising a tank divided transversely by a transverse partition into separate compartments, conveyer belts in said compartments over the water therein, the inner end portions of said belts 20 being adjacent to said partition whereby the articles to be washed are delivered by one of said belts to the other, driving means connected with one of said belts, and means connecting said belts together so that they 25 may be driven by said driving means.

6. A washing machine comprising a tank

divided transversely by a transverse partition into separate compartments, conveyer belts in said compartments over the water therein, the inner ends of said belts being 30 adjacent to said partition whereby the articles to be washed are delivered by one of said belts to the other, means disposed laterally with reference to said belts for throwing water laterally upon the articles 35 carried by said belts, and means above said belts adjacent to said partition for preventing water from splashing from one compartment to the other.

7. A washing machine comprising a tank 40 adapted to contain water, means for moving the articles to be washed over the water in said tank, laterally disposed means for throwing water from said tank upon the articles to be washed, and a transversely 45 disposed curtain depending in the path of the articles to be washed and adapted to be engaged thereby, said curtain being composed of a plurality of closely-hung pendants.

GEORGE S. BLAKESLEE.
